OFFSET PROOF PRESS MECHANISM

Harry C. Jones, New York, N. Y.

Application October 24, 1931, Serial No. 570,858

28 Claims. (Cl. 101—269)

This invention relates to mechanisms in which a cylinder is caused to roll upon a platen in such manner that the circumferential surface of the cylinder is in conformity with the surface of the platen over a definite length of travel.

For the purpose of illustration only, but by no means as restrictive of the invention, a typical direct-gearred impression-cylinder and bed press, such as an offset color proving press will be taken.

The diameter of the cylinder, when ready for use and including the blanket, and the pitch diameter of the gears driving the cylinder must be uniform or discrepancies in work produced will occur, and the impression will be of different size than the original image.

Where, as usual, the toothed racks, rigidly fixed to the sides of the stationary platen, in the plane of its operative surface, used to cause rotation of the gears secured to the ends of the cylinder shaft, adjustment can only be attained by building up under the blanket, which is difficult and takes time to do.

It is therefore an object of the present invention to provide positive mechanical means by which the circumferential surface of the cylinders, used in the foregoing type of mechanisms, and its movement over the platen surface, may be brought into correct relation.

A further feature is in the provision of means whereby both of the cylinder drive gears may be accurately adjusted in harmony.

Another purpose is to provide a compensating device for any inaccuracies in such cylinder and platen constructions whereby precision in results is readily attainable and without recourse to making changes in the diameter of the cylinders on the carriage in which they are mounted.

A further aim is to provide such devices in forms which may be applied to existing structures or incorporated in new machines.

These important objects, and others of analogous nature, are accomplished by the novel construction and arrangement of parts hereinafter described and illustrated in the accompanying drawings, forming a material part of this disclosure, and in which:

Figure 1 is a plan view of a conventional type of offset proving press in which is incorporated an embodiment of the invention.

Figure 2 is a side elevational view of the same.

Figure 3 is a transverse sectional view taken on line 3—3 of Fig. 2, and drawn to an enlarged scale.

Figure 4 is a fragmentary sectional view of

the rack adjusting device, the section being taken on line 4—4 of Fig. 5.

Figure 5 is a side elevational view of the same showing the rack and bar constructions.

Figure 6 is a fragmentary side view of one end 5 of the rack bar showing the adjusting means as moving the rack in one direction.

Figure 7 is a similar view showing the rack as moved in the opposite direction.

Stated in general terms, on offset proof presses 10 it is necessary to have the circumference of the roller, (cylinder), after a blanket has been put on it, exactly the same as the pitch circumference of the gears that drive it, in order to cause the print to be the same size as the image on 15 the plate, and also to prevent slurring of the print.

Many other machines, of similar structure and operation, require equal accuracy in adjustment, involving care, experience and valuable time. 20

One of the main objects of this invention is to provide means by which the exact amount of travel of a roller on a bed may be accurately adjusted, such adjustment being a divisional part of the amount of change, or increment, that 25 would be produced by altering the teeth in the driving gears.

This ability becomes useful (especially in color work) when it is desired to place an image, which is of continuous pattern nature, on a roller, because it is difficult to produce the original image of exactly correct size, and also difficult to get a series of rollers all being exactly of the same 30 diameter.

Referring now to the drawings in greater detail, the main frame of the machine is formed by a pair of upright stands 15 arranged in opposed relation and provided with upright elements to rest upon the floor, these stands being connected at spaced intervals by cross beams 16 40 which support a platen or bed 17.

This platen is level throughout its length and is provided with means—not shown—to secure upon it the article A to be copied and at another 45 point the subject B on which image of the article is to be imprinted.

Carried on the sides of the frame members are racks 18 provided with a plurality of spaced longitudinal slots 19 through which pass the bodies 50 of shouldered clamp screws 20 threaded into the frame.

Meshed with these racks are gears 21 fixed on the ends of a cylindrical roller 22 mounted on a shaft 23, journaled in a carriage, and provided 55

with means for rotation, as indicated by the handle 24.

The carriage consists of a light frame having side members 25 connected by a cross bar 26, over 5 the roller, the sides, at their lower extremities, having inreaching bosses 27 in which are received shouldered screws 28 carrying freely revoluble rolls 29.

These rolls travel on flanges 15' of the frame 10 sides and are held downwardly thereagainst by contact with the under side of the racks 18.

In order to compensate for any inaccuracies that may occur, the racks 18, as has been noted, are limitedly shiftable on the frame sides and 15 are adjusted in the following manner:

The frame sides 15 have forward extensions 30 containing vertical slots 31 to receive shouldered screws 32 provided with check nuts, and on which are pivotally mounted the ends of channelled bars 33.

Fixed in the inner sides of the carriage elements 25 are shouldered studs 34 carrying rolls 35 which travel in the grooves 33' of the channel bars.

25 The opposite ends of the channel bars 33 are increased in width, as at 36 and carry fixed cylindrical bosses 37 provided with visible indexes or points 38.

Adjacent the inner ends of the bosses are openings 39 leading to slots 40 in the walls of the bars, these slots being suited to receive closely fitted pins 41, the other, inner ends of which are similarly fitted to transversely oblique slots 42 in the outer end portion of the racks 18.

35 It will be obvious from the foregoing that as the roller carrying carriage is moved along the platen, in either direction, the racks will be forced in the opposite direction, due to the obliquity of the slots by reason of their engagement with the pins 41 which are fixed in definite relation to the channel bars 33, this arrangement being best seen in Figs. 6 and 7. This action also may be reversed.

45 Rigidly fixed, transversely in the pins 41 are micrometric screws 45, preferably left hand for convenience in operation, these screws engaging nuts 46 revoluble in the bosses 37, the outer extending ends of the nuts being knurled, as at 47, and provided with bevelled dials carrying graduations 48 readable in connection with the indexes 38.

The nuts 46 are prevented from longitudinal movement by collars 49 disposed in the openings 39 to abut the inner ends of the bosses 37 and 55 are held by set screws on the nut.

The extending ends of the screws 45 are provided with knurled nuts 50 to maintain the micrometer screws in adjustment.

60 Although the improvements have been described with considerable detail and with respect to certain particular forms of the invention, it is not desired to be limited to such details since many changes and modifications may well be made without departing from the spirit and scope 65 of the invention in its broadest aspect.

Having thus described the invention, what is claimed as new and desired to secure by Letters Patent, is:—

70 1. A machine having a bed, a rack at the side of said bed, a carriage movable over the bed, said carriage having a roller journalled therein, a gear on said roller meshed with said rack, and means to move the rack lengthwise while in mesh 75 with said gear, thereby to affect the amount of

rotary movement of said gear and roller relative to the bed on which said rack rests.

2. A machine having a bed, a rack at the side of said bed, a carriage movable over the bed, said carriage having a roller journalled therein, a gear on said roller meshed with said rack, means to adjust the rack longitudinally while engaged with said gear and means for controlling the rack adjusting means thereby to alter the amount of movement of the gear in relation to the bed on 10 which the rack is adjustably secured.

3. A machine having a bed, a rack carried by said bed, a roller on said bed having a gear meshed with said rack, and controlled means for continuously and uniformly moving said rack while 15 meshed with said gear, thereby to produce a uniformly different degree of movement for the gear in relation to the bed than would be produced by altering the number of teeth in the gear.

4. A machine having a bed, a roller to pass thereover, a driving means on said roller, an element adjustably connected to said bed, and means associated with said driving means for continuously moving said element with respect to 25 said bed while the driving means is moving so as to alter the travel of the roller relative to the bed.

5. A machine having a bed and a roller revoluble substantially in contact therewith, a pivoted lever-like element movable continuously with said roller, means to modify the surface movement of said bed and roller, said means operatively connecting the element and the roller.

6. A machine having a bed and a roller revoluble substantially in contact therewith, an element pivoted at one end and movable at the other in unison with said roller, and means operatively connecting the roller and the element to change the relative surface movement of said bed and 40 roller irrespective of direction of revolution of said roller.

7. A machine having a fixed bed, a rack longitudinally adjustable at the side of said bed, said rack having an oblique transverse slot, a carriage movable over the bed, a roller revoluble in said carriage, a gear at the ends of said roller meshed with said rack, a channel bar having an adjustable pivot attached to one end of said bed, a roll on said carriage operative in the channel 50 of said bar, and a pin carried at the opposite end of said bar operative in the rack slot.

8. A machine having a fixed bed, a longitudinal rack shiftable on said bed, said rack having a transverse oblique groove near one end, a carriage having a roller movable over said bed, a gear on said roller meshed with said rack, a bar alongside said rack, said bar having a vertically adjustable pivot at one end, means on said carriage to raise and lower said bar when moved over 60 said bed, a pin carried by said bar to operatively engage the oblique slot of said rack, and means to adjust the position of said pin relative to said bar.

9. A machine having a fixed bed, a longitudinal 65 rack shiftable on said bed, a carriage having a roller geared to said rack and movable relatively to the bed, and variable means actuated by said carriage to shift said rack whereby to increase and decrease the effective movement of the carriage relatively to the bed.

10. A machine having a fixed bed, a longitudinal 70 rack shiftable on said bed, said rack having a transversely oblique groove near one end, a carriage having a roller movable over said bed,

- 5 a gear on said roller meshed with said rack, a bar alongside said rack, said bar having a vertically adjustable pivot at one end, means on said carriage to adjust the height of said bar relative to said rack when moving over said bed, a pin carried by said bar to engage the oblique slot of said rack whereby to shift the rack endwise, and micrometric means on said bar to vary the position of said pin.
- 10 11. A machine having a fixed bed, a longitudinal rack shiftable on said bed, a carriage having a roller geared to said rack, means controlled by the movement of said carriage to increase and decrease the effective movement of the carriage relatively to the bed, and means independently adjustable to modify said controlling means.
- 15 12. A machine having a fixed bed, longitudinal racks shiftable on said bed, a carriage having a roller geared to said racks, means controlled by the movement of said carriage to increase and decrease the effective movement of the carriage relatively to the bed, and micrometric means independently adjustable for each rack to modify said controlling means.
- 20 13. A machine having a fixed bed, a carriage movable longitudinally thereover, a roller journaled in said carriage, rack bars limitedly slideable along the sides of said bed, gears on the ends of said roller to engage said bars thereby causing rotation of the gears, levers adjustably pivoted at one end of said bed, means on said carriage to adjust the height of said levers, and connections between said levers and bars whereby the bars are moved minutely lengthwise during travel of said carriage.
- 25 14. A machine having a fixed bed, a carriage movable longitudinally thereover, said bed having longitudinal slots in its sides, pairs of rolls on said carriage operatively engaged in the slots, a roller in said carriage to travel at a predetermined height above said bed, racks adjustably secured on the sides of said bed, gears at the ends of said roller in mesh with said racks, means operated by said carriage to adjust said racks longitudinally by minute increments, and means to control the amount of movement imparted by said adjusting means.
- 30 15. A machine having a fixed bed, a carriage movable longitudinally thereover, a roller journaled in said carriage, positive means for minutely enhancing and retarding the peripheral surface speed of said roller relative to the surface of said bed whereby complete concordance may be attained and means for adjusting said first named means.
- 35 16. A machine having a bed and a roller revoluble substantially in contact therewith, an element pivoted at one end and movable simultaneously with said roller, means associated with the other end of the element for predetermining the amount and the direction of the movement of said element, and means operatively connecting the element and the roller to modify the relative surface movement of said bed and roller.
- 40 17. A machine having a bed, a roller revoluble substantially in contact therewith, a pivoted lever-like element movable continuously with said roller, means for adjusting the swing of said element, and means operatively connecting the element and the roller to modify the surface movement of said bed and roller.
- 45 18. A machine having a bed and a roller revoluble substantially in contact therewith, an element pivoted at one end and movable at the other in unison with said roller, and means interposed
- 50 between the element and the roller to change the relative surface movement of said bed and roller, irrespective of the direction of revolution of said roller including a normally fixed member movable by said element.
- 55 19. A machine having a bed, a roller to pass over said bed, a movable rack, a gear on said roller meshed with said rack, a control element, means for operatively connecting the element to the rack to control the movement of the rack, and means for imparting movement to said element while the gear is meshed with the rack thereby to change the relative travel of said roller and bed.
- 60 20. A machine having a fixed bed, a longitudinal rack shiftable on said bed, a carriage having a roller geared to said rack, and means actuated by said carriage to shift said rack whereby to increase and decrease the effective relative movement of the carriage and the bed.
- 65 21. A machine having a fixed bed, longitudinal racks shiftable on said bed, a carriage having a roller geared to said racks, pivoted means controlled by the movement of said carriage to increase and decrease the effective movement of the carriage, and micrometric means independently adjustable for each rack to modify said controlling means.
- 70 22. A machine having a fixed bed, a carriage movable longitudinally thereover, a roller journaled in said carriage, bars limitedly slideable along the sides of said bed, means on the ends of said roller to engage said bars thereby causing rotation of the said means, levers adjustably pivoted at one end of said bed, means on said carriage to adjust the height of said levers, and connections between said levers and bars whereby the bars are moved minutely lengthwise during travel of said carriage.
- 75 23. In mechanism of the character described, a bed, a rotatable roller, means movable linearly relatively to the bed for supporting the roller, and means for maintaining equal the circumferential movement of the roller and the linear movement of said supporting means including a pair of cooperating members, one of said members being rotatable with the roller and linearly movable with said supporting means, and means operatively connected to said supporting means and to the other of said members for controlling the movement of the other member linearly of the bed.
- 80 24. In mechanism of the character described, a bed, a rotatable roller of variable outermost effective diameter, means for supporting the roller, means for rotating the roller, means engaging the roller rotating means for moving the roller linearly of the bed, and movable means operatively connected to the means for moving the roller linearly for positively maintaining equal the linear and the circumferential movements of the roller independently of changes in the effective diameter of the roller.
- 85 25. In mechanism of the character described, a bed, a revoluble roller mounted for movement linearly of the bed, and movable means operatively connected to the roller for positively maintaining equal the linear and the circumferential movement of the roller independently of changes in the effective outermost diameter of the roller including a pair of cooperating linearly movable members, and rigid means for moving one of said members linearly and through a predetermined part of the total linear movement thereof during

the corresponding part of the linear movement of the other member.

26. In mechanism of the character described, a bed, a revoluble roller mounted for movement linearly of the bed, and movable means operatively connected to the roller for positively maintaining equal the linear and the circumferential movement of the roller independently of changes in the effective outermost diameter of the roller including a pair of cooperating movable members, means for rotating one of said members, and means for linearly moving and controlling the movement of the other of said members.

27. A machine having a bed, a roller to pass over said bed, a rack, a gear on said roller

meshed with said rack, means engaging the rack and movable relatively to and supported by the bed while the gear is meshed with the rack for controlling the relative travel of said roller and bed, and means operatively connecting the gear and the control means to impart movement to said control means.

28. A machine having a bed and roller revoluble substantially in contact therewith, means, including an inclinable element pivoted at one end and movable simultaneously with said roller, for modifying the surface movement of said bed and roller, and means associated with said roller to actuate said element.

HARRY C. JONES. 15
